ROAD ROLLING MACHINE

George E. Trembly, Homewood, Ill., assignor of
one-fourth to Louis H. Ayer, Chicago Heights,
Ill.

Application July 5, 1934, Serial No. 733,700

11 Claims. (Cl. 94—50)

My invention pertains to road rolling machines of any type, by which more than two rollers are employed to more effectively and accurately roll a road surface to a desired contour, than is possible where but two rollers are employed. With the construction of my invention, elevations above and depressions below a desired road surface contour for which the machine may be adjusted in any particular case, are rapidly brought to the desired contour, by automatic changes in the distribution of the weight of the machine on its several rollers, so that a greater pressure is produced on an elevation by the roller engaging it, than the normal pressure exerted on the road-way by the same roller when moving along the desired road contour, and similarly that less than said normal pressure is exerted by said roller at a depression below said contour.

By my invention, I provide means for quickly and accurately establishing different relative elevations of the rollers employed in the machine, as desired, to the end that the machine may be employed to impart to the roadway substantially a flat surface, a desired degree of convexity, or a desired degree of concavity in the direction of travel of the machine. I am thus able to effectively establish a desired contour on level stretches of roads, and also on longitudinal crests and hollows that may be necessary parts of the road contour at different points.

In my machine, I provide means for positively driving two of the rollers, the third roller illustrated being the steering roller, to permit maintaining the traction of the machine under any and all conditions of operation, which driving means I preferably construct to drive one or both of said two rollers, as desired, since in many cases satisfactory traction may be maintained by driving but one of said rollers.

To adjust my machine for the several road contours above referred to, I preferably provide mechanism for establishing different desired elevations of the frame of the machine relatively to the steering roller, at the same time maintaining a fixed relation between the other rollers and the frame and securing effective driving of said other rollers by the motor of the machine for all adjustments of the machine for different road contours. I also provide indicating devices showing the adjustment of the machine as to road contour at any time. Said adjustment may be effected manually or by power, as desired, and the adjusting means may be operated hydraulically or mechanically, as preferred.

In some cases it may be desired to have no

vertical adjustment of the steering roller relatively to the frame of the machine, for which constructions I provide for adjusting the machine for different road contours, by mounting the other and power driven rollers on a supporting framework or frameworks in turn pivotally mounted on the frame of the machine, the desired elevations of the rollers relatively to each other being selectively effected by turning said framework or frameworks on their supports. With the latter construction, I provide means for maintaining a constant driving relation between the adjustable rollers and the driving motor, and devices for selectively driving one or both of the driven rollers illustrated, as desired.

The above and other objects of my invention will be best understood by reference to the accompanying drawings illustrating preferred embodiments thereof, in which

Fig. 1 illustrates my machine with a vertically adjustable steering roller, in side elevation, 20

Fig. 2 is a plan view of the rollers of the machine illustrated in Fig. 1, and shows the roller driving mechanism employed,

Fig. 3 is a vertical, sectional view to an enlarged scale through the axis of the supporting trunnion of the steering roller, taken longitudinally of the machine shown in Fig. 1, 25

Fig. 4 shows in front end elevation, the parts illustrated in Fig. 3,

Fig. 5 shows in plan view to an enlarged scale, the control valve shown in Fig. 1 for controlling the elevation of the front end of the frame of the machine,

Figs. 6 and 7 are vertical, sectional views of the structure shown in Fig. 5, taken respectively along the lines 6—6 and 7—7, 35

Figs. 8, 9 and 10 are horizontal, sectional views of the structure shown in Fig. 7, taken respectively along the lines 8—8, 9—9 and 10—10, 40

Fig. 11 is a vertical, sectional view to an enlarged scale of a part of the structure shown in Fig. 1, taken along the line 11—11, to illustrate the frame elevation indicator employed,

Fig. 12 shows in a view similar to Fig. 3, a modified means for changing as desired, the elevation of the front end of the frame of the machine, and gearing for operating said means, and

Fig. 13 illustrates in side elevation, further modified means for effecting different desired elevations of the rollers of the machine, relatively to each other.

Similar numerals refer to similar parts throughout the several views.

As shown in Fig 1, my machine consists of a frame 10, a rear roller 11, an intermediate roller 12 and a front roller 13, the latter being the steering roller and connected by a yoke 14 and a vertical trunnion 15 with the frame 10. The trunnion 15 carries mechanism below described for changing as desired, the elevation of the frame 10 relatively to the trunnion, by liquid under pressure in pipes 16 and 17 extending to a control valve 18 located in the cab 19 of the machine. The control valve is also connected by pipes 20 and 21 respectively with a pump 22 and a tank 23. The pump is supplied with liquid from the tank by a pipe 24.

The frame 10 carries an engine 25 having transmission and differential gearing 26 of any well known kind, not specifically illustrated, which as more clearly shown in Fig. 2, drives the jack shafts 27 and 28.

As shown in Fig. 2, each of the rollers consists of two parts, the parts of the roller 11 being spaced from each other and overlapping the outer ends of the parts of the intermediate roller 12, the latter in turn overlapping the outer ends of the parts of the steering roller 13. The roller 11 is supported on a shaft 29 having a fixed support, not shown, on the frame 10, the parts of said roller being driven respectively by chains 30 and 31 from the shafts 27 and 28, by engagement with gears 32, 33 and 34, 35 carried by said roller parts and said shafts 27 and 28. The pump 22 is driven by the shaft 28 through a chain 36. The shafts 27 and 28 also carry gears 37 and 38 respectively connected by chains 39 and 40 with gears 41 and 42 carried by the parts of the roller 12. The gears 37 and 38 carry first members of clutches 43 and 44 and are free to turn on the shafts 27 and 28, the other members of said clutches being splined on said shafts and connected with levers 45 and 46 pivotally supported at 47 and 48 and connected by links 49 and 50 with an operating lever 51 pivotally supported at 52. Movement of the lever 51 on its support 52, engages and disengages the members of the clutches 43 and 44 and thus a means is provided for driving both of the rollers 11 and 12, or the roller 11 only, as desired.

The parts of the roller 12 are supported for rotation on a shaft 53 carried by brackets 54 rigidly secured to the frame 10.

As shown in Fig. 1, the trunnion 15 carries a gear segment 55 for operation by gearing in a box 56, in turn operated by a shaft 57 extending to a hand wheel 58 in the cab 19, to turn said trunnion and steer the machine in a manner well known in the art.

As shown in Fig. 3, the trunnion 15 is bored to form a vertical cylinder 59 in which a piston 60 is mounted, said piston being secured to the lower end of a tubular piston rod 61, by a nut 62. The piston rod extends with a sliding fit through a head 63 closing the upper end of the cylinder 59. The piston rod is shouldered near its upper end and extends with a snug fit through a yoke 64 in which the piston rod is secured by a nut 65 engaging threads on the upper end of the piston rod. The nut is provided with a threaded aperture for receiving the threaded end of the pipe 17, from which aperture a passageway 66 in the nut communicates with the bore in the piston rod.

The pipe 16 is provided with a vertical portion 16a extending through the nut 65 and into and through the bore in the piston rod 61 to nearly

the lower end of the latter where said bore is constricted and provided with threads into which the lower end of the pipe portion 16a is tightly screwed. A passageway 67 continues from the pipe 16a through the piston rod 61 to its lower end, as a result of which liquid under pressure supplied to the pipe 16, is communicated to the cylinder 59 below the piston 60. The bore in the piston rod 61, is enough larger in diameter than the pipe 16a, to permit the free flow of liquid around said pipe, and the piston rod 61 is provided with a side aperture 68 just above the piston 60, as a result of which liquid under pressure supplied to the pipe 17, is communicated to the cylinder 59 above the piston 60.

The steering segment 55 is provided with a downwardly extending supporting hub 55a mounted with a turning fit in a bore therefor in the frame 10, which hub has a bore that is a turning fit on the trunnion 15. A feather key 69 engages the hub 55a and the trunnion 15 to prevent relative angular movement between these parts, at the same time permitting longitudinal movement of said trunnion through said hub. As shown in Fig. 4, the yoke 64 at its base, overlaps the segment 55 to hold the latter in its seat in the frame 10.

The nut 65 is provided with a gland 70 and suitable packing, to prevent leakage through the nut around the pipe 16a. Packing of any desired kind adapted to the purpose, is also employed in the head 63 around the piston rod 61 and around the piston 60, to prevent leakage of the liquid from the cylinder, and from one portion to the other of the cylinder.

As a result of the construction shown in Figs. 3 and 4, when liquid under pressure is supplied to the lower portion of the cylinder by the pipe 16 and back flow of the liquid in the upper portion of the cylinder, through the pipe 17 is permitted, the front end of the frame 10 is raised relatively to the yoke 14 and thus relatively to the steering roller 13, raising the lower surface of the roller 12 relatively to the road plane of the rollers 11 and 13, and a relation of the rollers 11, 12 and 13 to each other vertically, for rolling a convex roadway as illustrated by the line 71 in Fig. 1, may be established. Similarly, when liquid under pressure is supplied through the pipe 17 to the upper portion of the cylinder, and back flow of liquid from the lower portion of the cylinder through the pipe 16 is permitted, the trunnion 15 and the steering roller 13 are raised relatively to the front end of the frame 10, depressing the roller 12 relatively to the road plane of the rollers 11 and 13, and a relation of the rollers 11, 12 and 13 to each other vertically, for rolling a concave roadway as illustrated by the line 72 in Fig. 1, may be established. Again, by moving the piston 60 to a mid-position in its cylinder, the road surfaces of the rollers 11, 12 and 13 may be brought into the same plane for rolling a flat roadway, as illustrated by the line 73 in Fig. 1.

By holding the liquid in the pipes 16 and 17 for any position of the piston 60 in its cylinder, the particular relation to each other of the rollers thus secured, may be maintained until it is desired to effect some other relation thereof.

To afford a visual indication of the relation of the rollers to each other at any time, I provide the following structure. As shown in Figs. 1 and 3, the cylinder head 63 carries a vertically and upwardly extending plate 74, adjacent and to the rear of which a rod 75 carried by and extending upwardly from the nut 65, is disposed. As shown in Fig. 75

11, the plate 14 is provided with a graduated scale 16 in any desired system of units, and the rod 15 carries at its upper end, a pointer 17 co-operating with the scale 16, to indicate at any 5 time the elevation of the front end of the frame 10 relatively to the steering roller 13, the scale and pointer being so located as to be clearly visible to the operator in the cab 19. The indicating devices referred to, are removed in Fig. 4 to more 10 clearly show the relation of the remaining parts.

As illustrated in Figs. 5 to 7 inclusive, the control valve 18 consists of a casing or body having a tapered bore fitting a similarly tapered plug 78 to which the operating handle 18a is secured. The 15 body of the valve is provided with oppositely disposed passageways 79 and 80 extending substantially parallel with the plug and each other and connected by suitable bores 79a, 80a, with the pipes 20 and 21 respectively. The valve body is 20 also provided with bores 16a and 17a midway between the passageways 79 and 80 and extending from the pipes 16 and 17 respectively, into the tapered bore in the valve body. As shown in Fig. 25 8, the plug 78 is provided with opposite and circumferential ports 81 and 82 in the plane of the bore 16a, each of said ports extending around somewhat more than one-quarter of the circumference of the plug 78, said ports 81 and 82 being in communication respectively with the passageways 79 and 80 at all times. As shown in Fig. 10, the plug 78 is also provided in the plane of the bore 17a, with a circumferential port 83, extending around somewhat more than one-quarter of the circumference of the plug, and located mid-way 30 35 angularly between the ports 81 and 82, the port 83 being at all times in communication with the bore 17a. As shown in Fig. 9, the plug 78 is also provided between the planes of the bores 16a and 17a, with a circumferential port 84, extending 40 around somewhat more than one-half of the circumference of the plug, and located so that its central portion is midway angularly, between the ports 81 and 82. As shown in Figs. 5 and 6, the plug 78 is provided with an end lug 85 extending 45 away from the handle 18a, for engagement with stop lugs 86 and 87 carried by the valve body, limiting the angular movement of the plug to substantially ninety degrees, the plug being shown in Figs. 5 to 10 inclusive, in its neutral or mid-position 50 for which there is no flow of liquid under pressure, to or from either of the pipes 16 and 17.

As a result of the construction and connections of the control valve 18 above described, with the handle 18a in its neutral position, and with the 55 pump 22 in operation, there is no liquid flow to or from the pipe 16, since the bore 16a is not in communication with any of the valve ports or passageways, (Fig. 8); there is no liquid flow to or from the pipe 17, since the port 83 is not in communication with any of the valve ports or passageways, excepting the bore 17a, (Fig. 10); and under the action of the pump, liquid flows through the pipe 20, bore 79a, passageway 79, port 84, passageway 80, bore 80a to pipe 21, (Fig. 9), and from 60 said pipe to tank 23, and from said tank through pipe 24 to pump 22 (Fig. 1), thereby permitting the pump to be in continuous operation and instantly available for operating the adjusting devices, without the possibility of producing undesirable liquid pressures between adjusting operations of said devices.

Movement of the lug 85 into engagement with the stop lug 86, (Fig. 5), moves the port 82 to connect the bore 16a with the passageway 80, (Fig. 8); at the same time, the port 83 is moved

to connect the bore 17a with the passageway 79, (Fig. 10), and the port 84 is moved away from the passageway 79 and is in communication with the passageway 80 only (Fig. 9). This supplies liquid under pressure from the pump through pipe 5 20 to the pipe 17 through the port 83 and permits liquid to flow through the pipe 16 and port 82 to the passageway 80 and thus through pipe 21 to the tank 23. This lowers the piston 60 in the bore 59 and lowers the front end of the frame 10 on 10 the trunnion 15.

Movement of the lug 85 into engagement with the stop lug 87, (Fig. 5), moves the port 81 to connect the bore 16a with the passageway 79, (Fig. 8); at the same time, the port 83 is moved to connect the bore 17a with the passageway 80 15 (Fig. 10), and the port 84 is moved away from the passageway 80 and is in communication with the passageway 79 only (Fig. 9). This supplies liquid under pressure from the pump through pipe 20 to the pipe 16 through the port 81 and permits liquid to flow through the pipe 17 and port 83 to the passageway 80 and thus through the pipe 21 to the tank 23. This raises the piston 60 in the bore 59 and raises the front end of the 25 frame 10 on the trunnion 15.

The liquid employed to operate the adjusting devices may be oil, water or any other liquid that will operate as above described.

In constructing road rolling machines, it will 30 be understood that the center of gravity of the machine is usually placed well back of the center of the machine, to reduce the weight on the steering roller and make steering relatively easy, and to apply the larger part of the weight of the machine to the rear roller or rollers, to exert as much pressure as possible practically, on the roadway being rolled. In view of this, associating the adjusting devices with the steering roller as described, secures several marked advantages as 35 follows. First, the total lifting force required to raise the front end of the frame need be but from one-quarter to one-third the weight of the machine, which force is much more readily developed and effectively and accurately utilized for the purposes described, than if it were attempted to adjust the intermediate roller relatively to the frame, which in some cases might require a total 40 adjusting force of from eighty to eighty-five per cent of the weight of the machine. Second, the vertical movement of the front end of the frame 45 relatively to the steering roller in effecting any desired vertical displacement of the intermediate roller from the road plane of the steering and rear rollers, is much greater than said intermediate roller displacement, as a result of which the latter displacement may be secured to any desired amount much more accurately than if it were attempted to secure the same by moving said intermediate roller relatively to the frame and the rear roller. Third, by providing fixed supports 50 for the rear and intermediate rollers, insuring a permanent relationship between them, the accuracy of operation of the adjusting devices is maintained for long periods of operation of the machine, to a much greater degree than would be possible if it were attempted to adjust the intermediate roller relatively to the frame and to the rear roller, due to the wear that would inevitably occur in the movable connections of the 55 latter adjusting mechanism. Fourth, with my construction described, the relation of the rear and intermediate rollers to each other is maintained for all road contour adjustments of the machine, thus maintaining the weight distribu- 60 65 70 75

tion on said rollers for all operating conditions, and insuring that each of said rollers will do its intended part of the work under any and all operating conditions, which would not be the case. 5 if the intermediate roller were adjustable with any considerable amount of longitudinal movement relatively to the frame.

Another important advantage of the construction described, results from the provision for 10 driving both the rear and the intermediate rollers. For example, where the adjustment is for level road rolling and the road surface has elevations of considerable amount that must be flattened, nearly all the weight of the machine is at 15 times on the intermediate roller, at which times the rear roller practically loses its traction, and the machine would be stalled, but for the means provided to drive the intermediate roller.

It will further be observed, that as a result of 20 the adjusting liquid being practically non-compressible, any desired adjustment of the rollers may be accurately maintained for as long a time as desired, that the indicating devices give the operator a reliable indication of just what the 25 adjustment is at any time, and that any desired changes in said adjustment, whether large or small, may be quickly effected by operation of the control valve.

The devices described for securing and indicating the adjustment of the rollers, are illustrative only, and I may employ any equivalent constructions without departing from the scope of my invention.

In Fig. 12, I illustrate means that may be employed for effecting the described roller adjustments mechanically instead of hydraulically. As 35 shown in this figure, the steering trunnion 15a extends vertically through the front end of the frame 10a, and is connected with the steering segment 55b by a feather key 69a, and said segment is held in place in the frame 10a by an upwardly extending yoke 64a secured to the frame 10a in the same manner as above described for the corresponding parts shown in Fig. 3. The 40 trunnion 15a is hollow and is provided near its upper end, with a transverse web 90 through which the lower and shouldered end of a vertical screw 91, extends. The screw is held against vertical movement relatively to the web 90, by a nut 92 on the lower end of said screw, and free turning movement of said web relatively to said screw is permitted by thrust bearings 93 and 94 of any suitable kind, located between said web and the screw shoulder and nut respectively. The upper 45 and threaded end of the screw 91 extends through a clearance bore therefor in the upper portion of the yoke 64a and is engaged by a feather key 95 carried by the yoke 64a, to prevent turning of the screw in the yoke without interfering with vertical movement of the screw through the yoke. A 50 worm wheel 96 is supported by the yoke 64a, for turning movement around the screw 91, said worm wheel having internal threads fitting the threads on said screw. The worm wheel is held 55 against vertical movement relatively to the yoke, by screw keys 97, 97 carried by the yoke. The worm wheel 96 is engaged by a worm 98 carried by a shaft 99 extending to the cab 19a of the machine, where a hand wheel 100 is secured to said 60 shaft. The shaft 99 has mounted thereon, bevel gears 101 and 102 meshing with a bevel gear 103 carried by the upper end of a short vertical shaft 104, the lower end of said shaft 104 having secured thereto a bevel gear 105 meshing with a 65 bevel gear 106 carried by the jack shaft 28a, the

latter shaft corresponding with and also serving the same purpose as the jack shaft 28 shown in Figs. 1 and 2. The gears 101 and 102 are freely rotatable on the shaft 99, and are held in mesh with the gear 103 by collars 107 and 108 secured to the shaft 99. A clutch member 109 is mounted for sliding movement on the shaft 99 between the gears 101 and 102, and is restrained from turning movement on said shaft by a feather key engaging said member and said shaft. The gears 101 and 102 are provided with clutch members 101a and 102a for selective engagement by the clutch member 109, the latter clutch member being engaged by a lever 110 pivotally supported at 111, by which the clutch member 109 may be moved 15 into engagement with either of said clutch members 101a and 102a, or if desired, placed in an intermediate position engaging neither of said clutch members. The lever 110 is connected by a link 112 with a lever 113 pivotally mounted at 20 114 in the cab 19a. The machine in other respects than described, is preferably of the same construction as described above in connection with Fig. 1. The structure shown in Fig. 12 thus provides a means by which the front end of the 25 frame 10a may be raised or lowered as desired on the trunnion 15a, either by power by operation of the clutch member 109, or by hand by operating the wheel 100. If preferred, the power adjustment may be utilized to secure substantially the 30 adjustment desired, and then the hand wheel 100 may be used to complete the adjustment with any degree of accuracy required. In any event, the resulting adjustment secures the same results as above described in connection with Figs. 35 1 and 3, without requiring a liquid tank, a pump, a control valve and connecting piping. The shafts 99 and 104 are supported from the frame 10a by suitable bearings not shown, since the structure shown in Fig. 12 is in part diagrammatic. 40

In Fig. 13 I illustrate a modified means for adjusting the rollers to roll a desired road contour, without vertical adjustment of the front end of the frame relatively to the steering roller, but at the same time maintaining the distance between the rear and the intermediate rollers a constant at all times, and driving both of said rollers by gear trains which are unchanged in any way by adjustment of the machine for different road contours. 50

As shown in Fig. 13, my machine consists of a frame 10b, a rear roller 11b, an intermediate roller 12b and a front or steering roller 13b. The front roller 13b is mounted in a yoke 14b from which a vertical trunnion 15b extends through the front end of the frame 10b, said trunnion being capable of turning movement only, relatively to the frame, and provided with turning mechanism of the kind above described. The rollers 11b and 12b are mounted and are rotary on shafts 29b and 53b respectively, which shafts are secured to and supported at each end by a framework 115 pivotally mounted on the frame 10b by means of a trunnion 116 provided with a bore to receive one end of the corresponding jack shaft 28b, the trunnion 116 being supported by a bracket 117 secured to the frame 10b and extending outside of the framework 115 to support said trunnion. Each of the rollers is preferably constructed in two parts, and a motor, gearing and jack shafts 60 of substantially the construction shown in Figs. 1 and 2, are preferably employed to drive the rollers 11b and 12b. As indicated in Fig. 13, the jack shaft 28b carries gears connected by driving chains 118 and 119 with gears carried by the cor- 70

responding parts of the rollers 11b and 12b respectively. The other ends of the shafts 29b and 53b are supported from the other side of the frame 10b in the same manner as described, and 5 the other parts of the rollers 11b and 12b are similarly driven.

The framework 115 is provided with a forwardly extending arm 115a rigidly connected with the framework and in turn connected with the lower 10 end of a piston rod 120 connected at its upper end to a piston 121 in a cylinder 122, said cylinder being connected with the frame 10b at 123. The lower and upper portions of the cylinder 122 are provided with pipes 16b and 17b extending to 15 liquid pressure producing and controlling mechanism which, for example, may be of the construction illustrated in Fig. 1, and is not shown in Fig. 13. By movement of the piston 121 in the cylinder 122, the rollers of the machine may be adjusted for concave, flat and convex roadway contours indicated at 72b, 73b and 71b respectively with the results above described for the construction shown in Fig. 1. The arm 115a preferably has connected with it, an upwardly extending 20 rod 75b, the upper end of which is above the frame 10b and just back of a vertical plate 74b carried by said frame, said rod and said plate being provided with suitable indicating devices, for example, of the kind illustrated in Fig. 11, for 25 indicating to the operator of the machine, the adjustment of the framework 115 at any time. The framework supporting the other ends of the shafts 29b and 53b is preferably provided with similar adjusting and indicating devices.

30 My improved means for accurately rolling road contours of different kinds as described, may be applied to road rolling machines of any standard types, for example, tandem machines, and so called "three roller machines", with equally 35 advantageous results.

40 While I have shown my invention in the particular embodiments above described, it will be understood that I do not limit myself to these exact constructions as I may employ equivalents 45 known to the art at the time of the filing of this application without departing from the scope of the appended claims.

What I claim is:

1. In a road rolling machine, front, intermediate and rear rollers, a frame supported by said 50 rollers, said intermediate and rear rollers being mounted in fixed relation with respect to each other and to said frame, and said front roller being mounted on a trunnion pivotally mounted 55 in said frame for pivotal movement about a vertical axis and for vertical adjustment with respect to said frame in a plurality of parallel planes for vertically adjusting said front roller and the angle of said frame with respect to the 60 ground while said rear rollers remain fixed with respect to said frame for rolling different contours of roadways.

2. In a road rolling machine, front, intermediate and rear rollers, a frame supported by said 65 rollers, said intermediate and rear rollers being mounted in fixed relation with respect to each other and to said frame, a trunnion extending vertically through said frame and connecting said front roller with said frame for steering 70 purposes, and means for vertically adjusting said trunnion and front roller with respect to said frame in a plurality of parallel planes for establishing different positions vertically of said frame on said trunnion and varying the relationship of 75 said intermediate and rear rollers with respect to

the ground to permit said rollers to roll different contours of roadways.

3. In a road rolling machine, front, intermediate and rear rollers, a frame on said rollers, said intermediate and rear rollers being mounted 5 in fixed relation with respect to each other and to said frame, a trunnion extending vertically through said frame and connecting said front roller with said frame for steering purposes, and means for vertically adjusting said trunnion and front roller with respect to said frame in a plurality of parallel planes and holding said trunnion from vertical movement with respect to said frame for establishing different positions vertically of said frame on said trunnion and varying 10 the relationship of said intermediate and rear rollers with respect to the ground to permit said rollers to roll different contours of roadways.

4. In a road rolling machine, front, intermediate and rear rollers, a frame on said rollers, 20 a motor on said frame, drive connections between said motor and said intermediate and rear rollers for selectively driving said rollers, said intermediate and rear rollers being mounted in fixed relation with respect to each other and to 25 said frame, and said front roller being mounted for vertical adjustment with respect to said frame in a plurality of parallel planes and being adapted to be held in such positions of adjustment for varying the angular relationship of 30 the frame and rear and intermediate rollers with respect to the ground and permitting said rollers to roll different contours of roadways.

5. In a road rolling machine, front, intermediate and rear rollers, a frame on said rollers, a 35 motor on said frame, drive connections between said motor and said intermediate and rear rollers for driving said rollers, said intermediate and rear rollers being mounted in fixed relation with respect to each other and to said frame, said 40 front roller being mounted for vertical adjustment with respect to said frame in a plurality of parallel planes for varying the angular relationship of said frame and rear and intermediate rollers with respect to the ground and permitting said 45 rollers to roll different contours of roadways, and said drive connections for selectively driving said rollers including a selective clutch mechanism in the drive for one of said rollers.

6. In a road rolling machine, front, intermediate and rear rollers, a frame on said rollers, a 50 motor on said frame, drive connections between said motor and said intermediate and rear rollers for driving said rollers, said intermediate and rear 55 rollers being mounted in fixed relation with respect to each other and to said frame, said front roller being mounted for vertical adjustment with respect to said frame in a plurality of parallel planes for varying the angular relationship of said frame and rear and intermediate rollers with respect to the ground and permitting said 60 rollers to roll different contours of roadways, and said drive connections for selectively driving said rollers including a transverse shaft, a drive connection from said shaft to said rear roller, and a drive connection from said shaft to said intermediate roller including a selectively operable clutch.

7. In a road rolling machine, front, intermediate and rear rollers, a frame on said rollers, a 70 motor on said frame and drive connections from said motor to said intermediate and rear rollers, said intermediate and rear rollers being mounted in fixed relation with respect to each other and 75

to said frame, a trunnion extending vertically through said frame and connecting said front roller with said frame for steering purposes, and means for vertically adjusting said trunnion and front roller with respect to said frame for establishing different angular positions of said frame with respect to the ground for rolling different contours of roadways including a vertically disposed cylinder in said trunnion, a piston 10 movable in said cylinder and having connection with said frame whereby movement of said piston within said cylinder will cause movement of said trunnion with respect to said frame, and means for supplying fluid under pressure to said cylinder for holding pressure within said cylinder to hold said front roller in fixed positions of adjustment with respect to said frame.

8. In a road rolling machine, front, intermediate and rear rollers, a frame on said rollers, 20 said intermediate and rear rollers being mounted in fixed relation with respect to each other and to said frame, a trunnion extending vertically through said frame and connecting said front roller with said frame for steering purposes, and means for vertically adjusting said trunnion and front roller with respect to said frame for establishing different positions vertically of said frame on said trunnion for rolling different contours of roadways including a vertically disposed cylinder in said trunnion, a piston in said cylinder and having connection with said frame, and means for selectively supplying fluid under pressure to either end of said cylinder including a fluid pressure pump, a tank, pipes leading from 30 said pump and tank to said cylinder, and a single control valve for admitting or releasing fluid under pressure from either end of said cylinder and for holding pressure therein.

9. In a road rolling machine, front, intermediate and rear rollers, a frame on said rollers, 40 said intermediate and rear rollers being mounted in fixed relation with respect to each other and to said frame, a trunnion extending vertically through said frame and connecting said front roller with said frame for steering purposes, and means for vertically adjusting said trunnion and

front roller with respect to said frame and holding said trunnion from vertical movement with respect to said frame for establishing different positions vertically of said frame on said trunnions for rolling different contours of roadways, 45 and devices affording a visual indication of the relative elevation of said rollers to each other including a plate on the head of said cylinder and an indicating rod on said piston.

10. In a road rolling machine, front, intermediate and rear rollers, a frame on said rollers, a motor on said frame and drive connections from said motor to said intermediate and rear rollers, said intermediate and rear rollers being mounted in fixed relation with respect to each other and to said frame, a trunnion extending vertically through said frame and connecting said front roller with said frame for steering purposes, and means for vertically adjusting said trunnion and front roller with respect to said frame for establishing different positions vertically of said frame on said trunnion for rolling different contours of roadways including a screw and nut connected between said trunnion and frame, and a self-locking drive for effecting turn- 25 ing movement between said screw and nut.

11. In a road rolling machine, front, intermediate and rear rollers, a frame on said rollers, a motor on said frame and drive connections from said motor to said intermediate and rear rollers, 30 said intermediate and rear rollers being mounted in fixed relation with respect to each other and to said frame, a trunnion extending vertically through said frame and connecting said front roller with said frame for steering purposes, and means for vertically adjusting said trunnion and front roller with respect to said frame for establishing different positions vertically of said frame on said trunnion for rolling different contours of roadways including a screw having connection with said trunnion and projecting therefrom, a nut threaded on said screw and having connection with said frame, and a self-locking drive for turning said nut with respect to said screw.

GEORGE E. TREMBLY.
